UNITED STATES PATENT OFFICE.

LEONIDAS BISHOP, OF HARALSON, GEORGIA.

PLOWHEAD WITH DETACHABLE PLOWPOINT.

Application filed June 23, 1925, Serial No. 39,092.

This invention relates to improvements in plows and more particularly in plow points and has for its principal object to provide a plow point which may be readily and easily detached from the body portion so as to enable the plow point to be resharpened or replaced whenever necessary.

Another important object of the invention is to provide a detachable plow point where-
10 in the body portion therefor is adapted to be adjustably secured on the lower end of the plow stock or standard, the body portion being provided with an undercut for receiving the upper portion of the plow point
15 whereby the latter is held in proper position on the body portion.

A further object is to provide a detachable plow point of the above mentioned character which is simple in construction, inexpensive,
20 and further adapted to the purposes for which the same is designated.

Other objects and advantages of this invention will become apparent during the course of the following description.

25 In the accompanying drawing forming part of this specification, and in which like numerals are employed to designate like parts throughout the same:

30 Figure 1 is a front elevation of the device embodying my invention showing the same secured on the lower end of the plow stock or standard.

Fig. 2 is a side elevation thereof.

35 Fig. 3 is an enlarged detail perspective view of the body portion, and

Fig. 4 is a similar view of the plow point.

In the drawing wherein for the purpose of illustration is shown the preferred embodiment of my invention, the numeral 1 designates the lower portion of the usual plow stock or standard. A substantially rectangular shaped body portion 2 is provided with the central longitudinally extending slot 3 whereby the body portion may be adjustably supported on the lower end of the plow stock or share through the medium of the bolts 4 which extend through the slot and through a suitable opening provided therefor in the plow stock or standard.

50 The lower portion of the body portion which extends below the lower end of the plow stock or standard 1 is cut away as illustrated at 5 and the juncture of the cut away portion and the body portion is under-
55 cut as illustrated at 6 for a purpose herein-
after to be more fully described. The cut

away portion 5 is further provided with the openings 7 as more clearly illustrated in Fig. 3.

A plow point or ground engaging imple-
60 ment is designated generally by the numeral 8, the same being also of substantially rec-
tangular design, the lower end of the plow
point being cut away in an angle to provide
the sharp edge 9. The major portion of the 65
plow point is slightly curved as more clearly
illustrated in Figs. 2 and 4. The upper por-
tion of the plow point 8 is adapted to fit
against the cut away portion 5 and the up-
70 per edge of the plow point is beveled as il-
lustrated at 10 to cooperate with the under-
cut 6 in a manner as clearly illustrated in
Fig. 2.

The upper portion of the plow point is
75 provided with the openings 11 which are
adapted to register with the openings 7
formed in the cut away portion 5 of the body
portion 2 and suitable securing bolts 12 ex-
80 tend through the registering openings and
provide a means for detachably securing the
85 plow point in proper position on the body
portion. The heads of the bolts are adapted
to be disposed in the enlarged portions 13
provided therefor at the upper ends of the
openings 11 and the nuts 14 which are
85 threaded on the threaded ends of the bolts
engage the bottom of the cut away portion 5
of the body portion 2.

A plow point of the above mentioned con-
struction may be readily and easily detached
90 from the body portion so as to facilitate the
resharpening of the point or replacing the
same whenever it becomes necessary. Fur-
thermore the provision of the slot 3 in the
body portion 2 enables the latter to be readily
95 adjusted on the lower end of the plow stock
or standard.

The simplicity in which my improved de-
vice is constructed enables the parts to be
100 readily assembled and furthermore the plow
point will at all times be maintained in
proper position on the body portion when the
device is in use.

While I have shown the preferred embodi-
ment of my invention, it is to be understood
105 that various changes in the size, shape and
arrangement of parts may be resorted to
without departing from the spirit or sacrific-
ing any of the advantages of the appended
110 claim.

Having thus described my invention, what
I claim as new is:—

In a plow, the combination of a plow stock, a plow body portion having a longitudinal slot formed therein whereby the same may be adjustably secured on the lower portion 5 of the plow stock, the lower portion of said body portion having its front face cut away, an undercut provided at the juncture of the cut away portion and said body portion, a plow point having its upper portion adapted 10 to fit against the cut away portion of the

body portion and being of substantially the same thickness of the cut away front face of the body portion, the upper edge of the plow point being beveled to cooperate with the undercut, said cut away portion and the 15 upper portion of the plow point being provided with registering openings, and securing bolts extending therethrough.

In testimony whereof I affix my signature.
LEONIDAS BISHOP.
